FLEXIBLE SHAFT FABRICATING MACHINE

Wilmer P. Uhler, Tottenville, N. Y., assignor to
The S. S. White Dental Manufacturing Com-
pany, a corporation of Pennsylvania

Application December 22, 1944, Serial No. 569,381

12 Claims. (Cl. 57—17)

1

My invention relates particularly to that class of flexible shaft fabricating machines wherein a plurality of wire dispensing bobbins are so conveniently disposed that wire may be drawn therefrom and directed to the winding head which when rotated causes them to be coiled about a core which is being progressed longitudinally therethrough, and is especially directed to a novel form of wire winding nose over which the layer wires from the bobbins pass as they are helically laid upon the forwardly moving core.

In the fabrication of flexible shafting many difficulties have been encountered which have resulted in the production of shafting having regions in its length that have such inequalities as to render those portions unfit for use.

These inequalities have been due principally to variations in the tension on the core and to variations in the tension on the individual layer wires being wound in coiled relation thereon, which variations are caused principally by lack of uniformity of friction of the spool supporting members both in the spools which control the progression of the core and the layer wires alike, and to other friction incidental to the guiding of the wires to the point of fabrication.

These variations in tension tend to cause varying forces which may either effect excessive momentary back pressure against said winding nose or may tend to cause the core to momentarily forge forward so that the layer wires will not be uniformly controlled by the winding angle of the forward surface of the nose, but will be wound with open spaces between the coils of wire thus wound on the core and thereby destroy the desired uniformity of the layers of the shaft being fabricated.

In other words, the rate of advance of the longitudinally progressed core will be momentarily more rapid than the normal rate of advance which is equal to the diameter of the wires being laid in coiled relation on the core per revolution.

On the other hand, if back tensions against the longitudinally fixed nose become too great then one or more layer wires will not be laid down against the core because of the high tension required to lay the wire down into place, it may then ride over the previous turn or coil of wire for a revolution or a part of a revolution until the excessive tension is relieved and it is again permitted to drop back into its normal position on the core.

When this condition occurs, if the layer wire does not break it will be wound in raised condition beyond the diameter of the coils being laid

2

and will remain as a hump on the shaft layer being wound and when the next layer is coiled thereon it can be readily appreciated that it may not pass through the core guide aperture in the winding nose, in which event it may jam and possibly cause breakage, or if it does pass through it will cause a rough and irregular region which must later be rejected and result in a loss of a considerable length of shafting.

10 The principal objects of my invention are to provide a flexible shaft fabricating machine with a winding head having a longitudinally yielding wire laying nose, which for convenience of description may be termed a floating nose, and to 15 provide yielding means tending to force said nose forwardly against the layer wires being wound upon the core.

Other objects of my invention are to provide a flexible shaft winding head with a winding nose 20 mounted in a longitudinally reciprocating carrier, and to provide means arranged to limit the length of such reciprocation in accordance with the likely tensions of the core wire and the layer wires being laid thereon over said nose.

25 Further objects of my invention are to provide preloading means which conveniently includes a spring of such compressibility as to maintain the winding nose forced forwardly against the progressing layer wires in accordance 30 with the predetermined tension of the several layer wires being wound.

My invention includes wire guiding means comprising carboloy surfaces which may preferably include annular carboloy bushings mounted at 35 predetermined wire guiding regions, and which afford hard substantially non-wearing guides whereby the wires may be progressed with but a minimum of substantially uniform friction.

My invention further includes means for effecting 40 automatic stoppage of the machine in event any one of the several wires being drawn from the wire dispensing bobbins or spools should break or said bobbins become depleted without being noticed by the operator.

45 The form of my invention as hereinafter more specifically described comprises a flexible shaft fabricating machine in which a plurality of layer wire dispensing bobbins are coaxially mounted for rotation in a flier frame on a hollow shaft and the layer wires on said bobbins are led through 50 suitably disposed bushings to and through the flier head and over the winding nose to be coiled about a longitudinally progressed core.

The winding head essentially includes means 55 for permitting the winding nose to reciprocate

longitudinally to a limited extent incidental to variations in the tension of the layer wires being directed thereby to be coiled on the core and further includes yielding means such as a spring tending to force said winding nose forwardly against the layer wires passing thereover and tending to maintain a constant tension at the point of fabrication with the core.

My invention also includes all of the various novel features of construction and arrangement as hereinafter more definitely specified.

In the accompanying drawings, Figure 1 is a vertical longitudinal sectional view of a flexible shaft fabricating machine with certain parts shown in side elevation for convenience of illustration and showing but a fragment of the supporting table or base; Figure 2 is a transverse vertical sectional view of the machine illustrated in Figure 1, taken on the line 2-2 in said figure; Figure 3 is an enlarged fragmentary vertical longitudinal sectional view showing the winding head and its floating nose mechanism; Figure 4 is transverse vertical sectional view taken on the line 4-4 in Figure 1 and showing the details of the automatic stop mechanism; Figure 5 is a perspective view of the stop plunger guide plate; Figure 6 is a perspective view of the stop plunger retaining disc; and Figure 7 is a perspective view of one of the automatic stop plungers shown in Fig. 4.

In said figures, the base or stand 1 has supported thereon the journal supporting standards 2 and 3 terminating upwardly in the ball bearing journal boxes 4 and 5 respectively having the closure caps 6 and 7.

The journal box 4 carries the rearwardly disposed ball bearing, comprising the inner and outer ball races 8 and 9 respectively and the balls 10, which rotatably supports the rearwardly projecting trunnion 11 of the flier frame 12, and the journal box 5 carries the forwardly disposed ball bearing, comprising the inner and outer ball races 13 and 14 respectively and the balls 15, which rotatably supports the forwardly projecting trunnion 16 of the forward flier frame 17, which trunnion also conveniently provides the winding head 18.

The flier frames 12 and 17 are conveniently connected by the bars 19, 20, 21 and 22 and are rigidly engaged therewith by the nuts 23 and 24 to form the flier 25 which includes the shaft supporting spider 26 mounted for longitudinal adjustment on the frame connecting bars 19, 20, 21 and 22 but limited in its rearward adjustment by the collars 27.

The several layer wire dispensing spools 28, 29, 30 and 31 are mounted to rotate in the flier 25 upon the shaft 32 which extends through the trunnion 11 and is supported forwardly in the spider 26, and said shaft 32 is provided with a relative hard wear resisting inner tube 33 through which the core 34 is directed to and through the winding head 18.

The flier 25 may be conveniently rotated by the grooved pulley 35 which is mounted on the trunnion 11, keyed thereto by the key 36 and retained thereon by the nut 37 which is threadedly engaged with the free end of said trunnion.

The winding head 18 which is best illustrated in the enlarged view in Fig. 3, has the bore 38 which is provided forwardly with the internal screw threads 39 with which the rearwardly extending screw threaded nipple 40 of the annular fitting 41 having the forwardly projecting boss 42 is threadedly engaged.

Said boss 42 is encircled by the internally screw threaded annular wire guide bushing ring 43 which is engaged with said fitting 41 by the screws 44 and which carries the wire guide bushings 45 preferably formed of a wear resistant substance such as carboloy and providing eyes through which the layer wires 46, 47, 48 and 49 being drawn from the respective spools 28, 29, 30 and 31 pass.

An annulus 50 preferably formed of carboloy is mounted forward of said bushing ring 43 and is secured thereto by the annular retainer 51 which is rotatably fitted on said boss 42 in screw threaded engagement with the internal screw threads 52 of said bushing ring 43, and which has the radially extending flange 53 engaged with the shoulder 54 formed by the countersunk recess 55 in the bore of said annulus 50. The peripheral convex cheek 56 of the annulus 50 serves to direct the several layer wires 46, 47, 48 and 49 to the substantially conoidal winding nose 57 which lays them in coiled relation upon the core 34, while it is being progressed forwardly in a well known manner.

The layer wires 46, 47, 48 and 49 are thus drawn from their respective spools 28, 29, 30 and 31 from which they are directed through the suitably bushed wire guides 58 and 59, thence through the guide ring 60, the bushings 61 in the bushing carrier ring 62 which register with the passages 63 through which said wires 46, 47, 48 and 49 pass.

As said wires emerge through the outer cylindrical wall of the winding head 18, they pass through the annulus 64 which has the wear resisting liner 65 of a non-wearing substance such as carboloy and said wires are restrained thereby from centrifugal displacement as they pass over the respective automatic stop plungers 66, 67, 68 and 69, from which they are directed through the bushings 45 and over the annulus 50 to the winding nose 57 over which they ride as they are coiled about the core 34.

The winding nose 57 which may preferably be formed of a hard substance such as carboloy is mounted for a limited axial yielding movement so as to compensate for the inequalities in tension of the core and layer wires being coiled thereon and has its reduced cylindrical rearward extension 70 engaged in the socket 71 of the enlarged forward terminal region 72 of the tubular nose carrying spindle 73 which extends through the sleeve 74 and terminates rearward of the flier frame 17.

The forward end region of the sleeve 74 is engaged with the fitting 41 by the screw threads 75 and terminates forwardly well within the outer end of the boss 42 of said fitting 41, while the rear end region 76 is enlarged to provide the pocket 77 for reception of the coiled spring 78 and is provided with the external screw threads 79 with which the spring retaining screw cap 80 is engaged.

Said sleeve 74 is maintained centered in its longitudinally adjusted position in the bore 38 by the annular adjusting nut 81 which has its forward conoidal end surface 82 fitted against a similarly countersunk cooperating rear surface of the winding head 18; thus it will be seen that the axial relative position of said sleeve 74 and winding head 18 may be varied and when adjusted to the desired relation be rigidly maintained adjusted by said nut 81.

The winding nose carrier 73 is normally forced forwardly by the coiled spring 78 which bears forwardly against the buffer ring 83 which en-

circles said tubular nose carrier in engagement with the shoulder 84 thereon.

From the foregoing it will be obvious that the winding nose 57, and its carrier 73, as illustrated in Fig. 3, occupies a substantially medial position but may, as tensions on the wires vary, be forced forwardly by the coiled spring 78 until the buffer ring 83 engages the forward wall 85 of the spring pocket 77, or said winding nose 57 be forced inward until the shoulder 86 formed by the enlarged forward terminal region 72 engages the forward end 87 of the sleeve 74. Said nose carrier 73 is also provided with the lock ring 88 disposed in the groove 89 adjacent the rear end of said carrier.

Referring now to the automatic stop mechanism, the stop plungers 66, 67, 68 and 69 are slidably mounted for radial movement in the slots 90, 91, 92 and 93 in the axially extended flange 94 of the annular plunger guide plate 95, which, as best illustrated in Figs. 4 and 5, is secured to the fitting 41 by the screws 96, 97 and 98 which are extended through the countersunk apertures 99, 100 and 101 in said plate 95, and said plungers 66, 67, 68 and 69 are retained in their respective slots 90, 91, 92 and 93 by the plunger retaining disc 102, see Figs. 3 and 6.

As is best illustrated in Figs. 4 and 7, the automatic stop plungers 66, 67, 68 and 69 are respectively provided with the stop lugs 103, 104, 105 and 106, which cooperate with the flange 94 to limit their outward thrust and thereby to prevent them from accidentally falling out, and said plungers may be provided with the wear resisting tips 107, 108, 109 and 110 respectively having the wire guiding grooves 111, 112, 113 and 114.

As best illustrated in Fig. 4, the stop plungers 66, 67, 68 and 69 are encircled by the collector ring 115 which is thus supported by the angle plate 116 whose foot 117 is secured to the bracket 118 by the stud bolts 119 and 120 with the interposed insulation pads 121, 122 and 123, and said ring 115, which is secured to the angle plate 116 by the screws 124, 125, and 126, serves, in event of breakage of any of the layer wires 46, 47, 48 and 49, as a sliding contact for the individual plunger thus released by said broken layer wire and is centrifugally shot outward to slidably engage said ring 115 and thereby cause through the electrically connected wire 127 stoppage of the motive power which actuates the flier 25 comprising the connected flier frames 12 and 17, in a well known manner.

It may here be noted that as tensions on the spools vary or increase as the tension in the core and layer wires vary, the nose piece will be depressed a greater or lesser amount. As the tensions increase, the nose piece is depressed, thus compressing the spring so that as the nose is forced rearwardly by the increasing tensions, the force required to wedge or draw the layer wires down into position against the core is increased. The nose piece therefore may be said to be floating to the extent that it is constantly moving back and forth to balance existing stresses and tensions incident to fabrication of the layers on the core.

The so termed floating nose, therefore, has desirable advantages in that it enables limitation of the forward pressure and serves as an indicator to the operator that the machine is functioning properly and producing good shafting.

My invention is advantageous in that the yieldingly mounted winding nose so compensates

for the variance in tension of both the core and the layer wires that said layer wires are laid in uniformly coiled relation about the core to produce continuously progressed fabricated flexible shafting substantially free from flaws or inequalities.

Furthermore, the automatic stop mechanism comprising the centrifugally actuated plungers which are normally maintained retracted by the progressing layer wires is effective to control the actuation of the machine, for should any of the plunger retaining layer wires break, its respective plunger will be centrifugally shot forward to engage the collector ring which is insulated from the bed or supporting frame of the machine and is electrically connected to a solenoid, the other side of which is grounded to said bed or supporting frame, sufficient current being introduced into the circuit to operate such solenoid which may be connected to actuate the switch and thereby shut off the power that actuates the spool carrying flier in an obvious manner, whereby said flier will be instantly brought to a stop and the usual snarling of the wires will be averted.

I do not desire to limit my invention to the precise details of construction and arrangement as herein set forth, as it is obvious that various modifications may be made therein without departing from the essential features of my invention as defined in the appended claims.

Having thus described my invention, I claim:

1. A flexible shaft fabricating machine having a wire guiding flier head, through which a core may be passed, and in which is mounted for relative longitudinal movement a tubular spindle terminating in a nose arranged to direct a plurality of layer wires on to said core while moving therethrough, and a spring tending to force said spindle forward, against said layer wires which are free to slide thereover.

2. A flexible shaft fabricating machine provided with a wire guiding winding head having a bore through which a core may be progressed forwardly, a tubular spindle extending through said bore guiding said core, mounted for axial movement therein and terminating forwardly in a winding nose whose forward free face is arranged to direct a plurality of layer wires in coiled relation about said core, and means tending to yieldingly force said spindle forwardly.

3. A flexible shaft fabricating machine provided with a wire guiding winding head having a bore through which a core may be progressed forwardly, a tubular spindle extending through said bore and through which said core is directed and which is mounted for a limited slight axial movement therein and terminating forwardly in a conoidal winding nose arranged to freely direct a plurality of layer wires into coiled relation about said core, and spring means tending to urge said spindle forwardly.

4. A flexible shaft fabricating machine provided with a wire guiding winding head having an axial bore through which a shaft core may be progressed forwardly and having a plurality of passageways through which layer wires may be directed, an axially adjustable sleeve extended through said bore, a tubular spindle slidably mounted to reciprocate in said sleeve and terminating in a nose arranged to direct a plurality of layer wires into coiled relation about said core, and unincumbered means tending to freely urge said spindle forwardly whereby to lay said layer wires uniformly on said core.

5. A flexible shaft fabricating machine provided with a wire guiding winding head having an axial bore through which a shaft core may be progressed forwardly and having a plurality of passageways through which layer wires may be directed, an axially adjustable sleeve extended through said bore, and including an enlargement affording a pocket, a tubular spindle slidably mounted to reciprocate in said sleeve and terminating forwardly in an enlargement providing a shoulder cooperative with the forward end of said sleeve to limit its rearward movement therein and also providing a socket arranged to receive a replaceable wear resisting nosepiece arranged to freely direct a plurality of layer wires into superposed coiled relation about said core, and a coiled spring enclosed in said pocket and tending to force said spindle and its nosepiece forwardly.

6. A flexible shaft fabricating machine provided with a wire winding head through which a core may be progressed, a sleeve extended therethrough, a tubular spindle slidably mounted to reciprocate in said sleeve and terminating in a nose arranged to direct a plurality of layer wires into coiled relation about said core, yielding means tending to force said spindle forwardly, a wire guide secured to said head and having a plurality of circularly spaced apertures through which the layer wires are free to pass, an annulus of wear resisting material disposed between said wire guide and said nose, over which said wires are passed to said nose.

7. A flexible shaft fabricating machine provided with a wire winding head through which a core may be progressed, a sleeve extended therethrough, a tubular spindle slidably mounted to reciprocate in said sleeve and terminating in a nose arranged to direct a plurality of layer wires into coiled relation about said core, yielding means tending to force said spindle forwardly, wire guides disposed closely adjacent each end of said head and respectively having a plurality of circularly spaced apertures through which the layer wires may pass, an annulus of wear resisting material disposed between the forward wire guide and said nose, over which said wires are passed to said nose.

8. A flexible shaft fabricating machine provided with a wire winding head through which a core may be progressed, a tubular spindle extended through said head and mounted for limited reciprocation therein, and having a forwardly extended nose arranged to direct a plurality of layer wires into coiled relation about said core, yielding means tending to force said spindle forwardly, an annular wire guide having an axially curved inner surface disposed adjacent the rear region of said head, an annular wire guide hav-

5
8
ing an axially curved outer surface disposed adjacent the forward region of said head, and means on said head arranged to circularly space a plurality of layer wires which are drawn over said inner and outer surfaces as they travel to said nose.

9. A flexible shaft fabricating machine provided with a wire winding head, a reciprocatory hollow spindle terminating forwardly in a wire winding nose having an unincumbered forward surface, means arranged to limit the reciprocatory movement of said spindle and nose, and yielding means tending to force said spindle forwardly to maintain a uniform tension between said nose and the wires passing thereover.

10. A flexible shaft fabricating machine provided with a rotatable wire winding head, an axially adjustable sleeve extended through said head, a reciprocatory tubular spindle mounted to longitudinally reciprocate in said sleeve and terminating in a wire winding nose having a free conical forward surface, and a spring tending to force said spindle and its nose forwardly.

11. A flexible shaft fabricating machine provided with a rotatable wire winding head, an axially adjustable sleeve extended through said head and providing a spring pocket, a reciprocatory tubular spindle mounted for longitudinal reciprocation in said sleeve and terminating in a wire guiding nose, a spring disposed in said pocket tending to force said nose forwardly into tensional contact with the wires freely passing thereover, and means arranged to retain said spring in said pocket.

12. A flexible shaft fabricating machine having a winding head through which a core and layer wires are directed, a winding nose mounting free to reciprocate in said head and yieldingly forced forwardly against the layer wires passing over the forward surface of said nose to said core, said layer wires being the sole restraint of the forward thrust of said winding nose in its normal working axial positions.

WILMER P. UHLER.
